[57] CLAIM

The ornamental design for a pet food bowl, as shown and described.

DESCRIPTION

FIG. 1 is a perspective view from the top and side of the pet food bowl showing my new design;

FIG. 2 is a top plan view thereof;

FIG. 3 is a side elevational view thereof, with all side views being the same; and

FIG. 4 is a cross-sectional view thereof taken along line 4—4 of FIG. 2.

FIG-1

FIG-2

FIG-3

FIG-4
